UNITED STATES PATENT OFFICE.

ALLEN S. ERQUHART AND JAMES C. HUMMEL, OF COALINGA, CALIFORNIA.

PIPE-WRENCH.

1,030,881.

Specification of Letters Patent

Patented July 2, 1912.

Application filed February 24, 1911. Serial No. 610,647.

To all whom it may concern:

Be it known that we, ALLEN S. ERQUHART and JAMES C. HUMMEL, citizens of the United States, residing at Coalinga, in the 5 county of Fresno and State of California, have invented a new and useful Pipe-Wrench, of which the following is a specification.

This invention has reference to improvements in pipe wrenches or tongs and its object is to provide a wrench especially adapted for use in connection with deep well casings, wherein a single wrench is adapted without change to be used for the screwing 10 together or unscrewing of casings of different diameters, while those parts of the wrench which are liable to wear are readily replaceable and the wrench may at any time be restored to its original condition of use- 15 fulness at a very small cost.

The wrench comprises a handle member with a loop at one end made up of a number of link structures so disposed that the loop may be brought into contracting relation to a pipe or casing, whereby the movement of the handle to screw up or unscrew the pipe will tend to cause an increasing grip on the pipe, so that the wrench will not slip thereon, but on the application of a 20 suitable force to the handle, the pipe will be turned in the desired direction, while the movement of the handle in the other direction will immediately loosen the wrench from the pipe. Furthermore, the loop is 25 readily separable at a convenient point for the introduction of the wrench on the pipe or the removal of the wrench therefrom, although this separation of the wrench is not necessary where the wrench is applied 30 to an unconnected end of the pipe.

The invention will be best understood from a consideration of the following detailed description, taken in connection with the accompanying drawings forming a part 45 of this specification, with the understanding, however, that while the drawings illustrate a practical embodiment of the invention it is susceptible of other embodiments differing in details of construction from the 50 showing of the drawings, and, therefore, the invention is not confined to the exact form delineated in the drawings.

In the drawings:—Figure 1 is a plan view of the wrench as applied to a pipe or casing, 55 the latter being shown in cross section. Fig. 2 is a longitudinal section of a portion of the

wrench on a plane parallel with the face of the wrench and showing it applied to a pipe of smaller size than in Fig. 1. Fig. 3 is a section on the line 3—3 of Fig. 1. Fig. 4 is a section on the line 4—4 of Fig. 1. Fig. 5 is a perspective view of a connecting pin which may be employed. Fig. 6 is a perspective view of one of the links of the pipe grasping loop. Fig. 7 is a perspective view 60 of the serrated pipe engaging jaws or blocks.

Referring to the drawings, there is shown a handle member 1 which may comprise a straight bar of suitable cross section depending upon the size of the wrench and the material from which it is made, but this handle member 1 is always made of sufficient strength and the proper material to withstand any strain which may be put upon it. At one end the handle member 1 is formed 70 into an eye 2 and at the other end is formed with an ear 3, while adjacent to the end having the ear 3 the handle member is provided with another ear 4 projecting at substantially right angles to the handle and the 75 body of the latter is cut away on opposite sides of the ear to form recesses 5.

The ears 3 and 4 are connected to opposite ends of a loop composed of links 6, 7, and 8, and a compensating connecting member 9, 80 but this particular number of links is not mandatory, since a greater number of links may be used, although in the majority of cases the number of links shown will be ample.

In Fig. 6 the link 6 is shown separately, but as the link 7 is identical with the link 6 a description of the link 6 will apply equally to the link 7. Each link is curved on the arc of a circle and is provided with 90 a central boss 10 and terminal ears 11, 12, respectively, there being a single ear 11 and a pair of spaced ears 12 at the respective opposite ends of the link, the ear 11 being designed to enter between corresponding 95 ears 12 of the next link, while the ears 12 of the link 6 are designed to embrace the ear 3 of the handle 1 to be there held by a pivot pin 13 traversing the ears 12 and the intermediate ear 3, so that the link 6 is pivotally connected to the corresponding end 100 of the handle 1. The ear 11 of the link 6 enters between the ears 12 of the link 7 and is there pivotally held by a pivot pin 14.

The link 8 is longer than either the link 110 6 or 7 and is compoundly curved having one end 15 curved into general conformity with

the links 6 and 7 and the other end 16 reversely curved, while at an intermediate point there is formed a boss 17 like the boss 10 of either link 6 or 7. The end 15 of the link 8 terminates in spaced ears 12 and the end 16 of the link 8 terminates in a single ear 11. The ears 12 of the end 15 of the link 8 embrace the corresponding ear 11 of the link 7 and a removable pivot pin 18 is provided with a beveled end 19 and at the opposite end a head 20 carrying an eye 21 or other manipulating means, so that the pin 18 may be readily inserted or withdrawn from connecting relation to the ears 11 and 12 of the respective links 7 and 8, whereby the links 7 and 8 may be connected or disconnected at will to permit the application or withdrawal of the wrench from a pipe as desired.

20 The compensating member 9 differs from the links 6, 7 and 8 in having pairs of ears 12 at each end, the ears 12 at one end embracing the ear 4 of the handle and are pivotally connected thereto by a pivot pin 22, while the ears 12 at the other end of the link 9 are in embracing relation to the ear 11 of the extension 16 of the link 8, and these ears are connected together by a pivot pin 23 having a head 24 at one end and a manipulating eye 25 on the said head, while the other end of the pin 24 is formed with an extension 26 of reduced diameter terminating in screw threads, to which may be applied a nut 27 having a manipulating ring 28 or other means of turning the nut, so that the pin 23 is in effect a bolt permitting the connection and disconnection of the links 8 and 9 at their respective ends when such may be desired.

40 Each boss 10 and 17 is provided on the inner curved or concaved face with a recess 29 extending transversely to the length of the link, and centrally through this recess in radial relation to the axis of curvature of the boss there is formed a perforation 30 entered by a threaded passage 31 extending to one exposed face of the boss, this passage 31 being designed for the reception of a set screw 32. The recess 29 is designed to receive a head 33 having a serrated face 34, and projecting from the side remote from the face 34 the head 33 is provided with a stem 35 designed to traverse the passage 30 and to be engaged by the set screw 32. The serrations 34 extend in the same direction as the length of the recess 29 and when these serrations or teeth are applied to a pipe they extend lengthwise thereof.

60 All the heads 33 which constitute the gripping members of the wrench may be serrated, or some may be serrated and others smooth, depending upon the size of the wrench and the gripping action desired, but in either instance the heads 33 constitute 65 the sole pipe engaging portions of the

wrench and as these are the portions particularly subject to wear, it will be seen that should the active faces of these heads become worn they may be readily removed and thrown away and new heads substituted, since they may be very cheaply produced.

In Fig. 1 the wrench is shown applied to a pipe or casing 36 and in Fig. 2 the wrench is shown applied to a casing 37 of smaller 75 diameter, the application of the wrench in each figure being such as would result in the unscrewing of the pipe were the wrench moved in the proper direction, which as viewed in the drawings is counterclockwise, 80 the pipe threads being usually right-hand threads.

The wrench is placed upon the pipe by separating the loop made up of the several links either by disconnecting the links 7 and 8 by the withdrawal of the pin 18, or by disconnecting the links 8 and 9 by the removal of the pin or bolt 23, but in either instance after the loop end of the wrench has been placed in encircling relation to the body of 90 the pipe the removed pin is replaced, and then upon applying a force to the handle 1 in the proper direction, the serrated faces of the heads 33 are brought into engagement with the outer surface of the pipe at suitably spaced points therearound. Further movement of the handle 1 tends to carry the pin 13 toward the end 16 of the link 8, and at the same time the end 16 of the link 8 is urged toward the pin 13, the forces acting 100 mutually, but the forces are resisted by the engagement of the heads 33 with the pipe, so that the serrated faces 34 are forced into gripping engagement with the outer surface of the pipe, which gripping relation is sufficient to prevent slipping of the wrench upon the pipe and, the force being sufficient, the pipe is constrained to rotate in a direction which in the particular showing of the drawings tends to unscrew the pipe from another pipe to which it is assumed to be screwed, usually through the intermediary of a suitable coupling. The more force there is applied to the handle 1 the tighter will the device grip the pipe.

110 The active movement of the handle 1 is away from the link 8, but this link is prevented from moving because of the engagement of its gripping head 33 with the pipe. The link 9 under these circumstances becomes a compensating pivot connection between the end 16 of the link 8 and the ear 4 of the handle 1. The result of this is that the handle 1 becomes a lever of the first order with the ear 3 on the shorter end and the link 6, and following it the link 7 is brought toward the pipe until the gripping heads 33 carried by these two links tightly grip the pipe, thus arresting further movement of the lever independent of rotative 125 movement of the pipe.

movement of the pipe, and when this point is reached, further force applied to the handle 1 in the same direction as before will, because of the gripping relation of 5 the faces 34 of the heads 33 with the pipe, cause the latter to turn.

By arranging the parts so that the gripping heads 33 between them embrace an arc greater than one hundred and eighty degrees, the wrench cannot disengage from the 10 pipe, and the latter must turn.

Because of the flexibility of the loop the gripping heads may be brought closer together until they are about equi-distantly 15 disposed or approximately one hundred and twenty degrees apart, and this will usually determine the minimum size of pipe that the wrench will operate upon, while the expansion of the loop so that the arc embraced 20 by the three heads 33 is somewhat greater than one hundred and eighty degrees will determine the largest size pipe that the wrench will operate upon, but it will also operate upon all intermediate sizes.

25 The work the wrench will do is limited only by the strength of the material used, while at the same time but few parts are provided, and those parts liable to rapid wear are readily replaceable. The wrench 30 may at any time be restored to its original efficiency after the jaws or heads 33 have become worn by replacing such jaws with new ones at but slight cost. These jaws are seated in the recesses 29 with only the portions immediately back of the serrated faces 35 projecting, whereby the twisting strain is borne by the bosses 10 and 17, respectively, and the pins or projections 35 are relieved from such strain and may be utilized solely 40 for holding the jaws to the respective links

without liability of loss, but in such manner that these jaws may be readily relieved from the fastening means and removed when such operation is desired.

What is claimed is:—

45 A pipe wrench comprising a manipulating handle and a pipe embracing loop at one end of the handle expandible and contractible to include pipes of different diameters, said loop comprising two like links connected end to end, and one of said links being connected to the end of the handle, and a third link connected at one end to the link remote from the handle, said third link being of a length substantially that of the sum 50 of the first named links, said first named links and a portion of the third link being curved to like extents with relation to a common axis, and the third link being reversely curved at the end remote from its connection to the first two links, and a compensating connecting member pivoted at one end to the reversely curved end of the third link and at the other end pivoted to the handle at a distance from the end of the latter to 55 which the first named links are connected, all three links being provided with pipe engaging devices spacing the links from the pipe to be engaged, and said pipe engaging devices being in all pipe engaging positions 60 so disposed as to include an arc of more than one hundred and eighty degrees.

In testimony, that we claim the foregoing as our own, we have hereto affixed our signatures in the presence of two witnesses.
